(57) **CLAIM**

The ornamental design for a connector for a reticle box, as shown and described.

DESCRIPTION

FIG. 1 is a perspective view of a connector for a reticle box showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is another perspective view of FIG. 1;

FIG. 9 is another perspective view shown in environmental use; and,

FIG. 10 is another perspective view shown in an alternate environment.

The broken lines shown represent environmental subject matter and forms no part of the claimed design.
